UNITED STATES PATENT OFFICE.

JAMES A. HENSEY, OF ONEONTA, NEW YORK.

DESIGN FOR A COIN-COLLECTOR.

57,042.

Specification for Design.

Patented Feb. 1, 1921.

Application filed August 4, 1919. Serial No. 315,321. Term of patent 7 years.

To all whom it may concern:

Be it known that I, JAMES A. HENSEY, a citizen of the United States, residing at Oneonta, in the county of Otsego and State of New York, have invented a new, original, and ornamental Design for Coin-Collectors, of which the following is a specification, reference being had to the accompanying drawing, forming part thereof.

The figure is a perspective view of a coin collector showing my new design.

I claim:

The ornamental design for a coin collector, as shown.

JAMES A. HENSEY.
